T. Lator,
Indicator Lock.

No. 80,637

Patented Aug. 4. 1868.

Inventor:

Thomas Lator.

United States Patent Office.

THOMAS LALOR, OF TORONTO, CANADA, ASSIGNOR TO JOHN DEWE, GEORGE HARDING, AND BARTHOLOMEW LALOR.

Letters Patent No. 80,637, dated August 4, 1868.

IMPROVEMENT IN INDICATOR-LOCKS.

The Schedule referred to in these Letters Patent and making part of the same.

RECORDED

TO ALL WHOM IT MAY CONCERN:

Be it known that I, THOMAS LALOR, of the city of Toronto, in the Province of Ontario, and Dominion of Canada, have invented a new and useful Detector-Lock; and I do hereby declare that the following is a full, clear, and exact description of the same, which will enable others skilled in the art to make and use the same, reference being had to the accompanying drawings, and to the letters of reference thereon.

Figure 1 represents a side view of the key of my improved lock.

Figure 2 is a face view of the lock, showing the face-plate removed.

Figure 3 is a detail face view of the lock, without the face-plate and tumblers.

Figure 4 is a face view of the lock, without the front plate that covers the indicating-wheels.

Figure 5 is an edge view of the lock.

Figure 6 is a full face view of the lock.

Figure 7 is a detail perspective view of the cylinder by means of which the indicator-wheels are operated.

Figure 8 is a detail sectional view, taken on the plane of the line $z-z$, fig. 6.

Figure 9 is a sectional view, taken on the plane of the line $y-y$, fig. 2.

Similar letters of reference indicate corresponding parts.

The nature of my invention consists in providing the lock with wheels or indicators, each marked with the figures 0 and 1 to 9, inclusive, which wheels or indicators are connected with certain machinery inside the lock, hereinafter described, so that the lock cannot be opened without a change being made in the numbers on the said indicators, as seen through a number of small apertures in the face of the lock.

The figures on the said indicators are capable of nine hundred and ninety-nine, or more, or less, changes, which changes cannot be repeated without the destruction of a seal, made of lead or other material.

To enable others skilled in the art to make and use my invention, I will proceed to describe its construction and operation.

In the drawing—

A represents a padlock-case.

B the front plate of the same.

The invention may, however, be also applied to locks of other shape and kind.

Inside the lock is fitted a rotating cylinder, a , on which a ratchet-wheel or flange, p , is formed. This cylinder is connected with a spring, b , which prevents it from ever turning in the direction of the arrow, 1, figs. 2, 3. This cylinder is acted upon by a slide-bolt, d , fig. 3, which, being pushed upwards by the turning of the key, c , figs. 1 and 5, causes the cylinder to turn sufficiently in the direction of the arrow 2 to let the spring b catch into another tooth, and, by its motion, to turn also a wheel or indicator, f , fig. 4, fitted to the axle of the cylinder. The cylinder, after this partial revolution, is locked by the two tumblers, e , fig. 2, the hook-shaped ends, r , of which fit into apertures or indentations formed in or through the sides of the cylinder, which tumblers are released by the action of the key, at the same time that the slide-bolt, d , fig. 3, is pushed upwards.

When the key is inserted, it first acts on the tumblers, so as to free the cylinder, and to allow the slide to be raised, and it then raises the slide, so as to turn the cylinder. The slide-bolt is replaced in its original position by the turning back of the key after the lock has been opened.

Attached to the slide-bolt d , fig. 3, there is a guard, p' , figs. 2 and 3, which, when the slide-bolt is replaced in its original position, as above described, completely covers the face of the locking-bolts n , fig. 2, so that no access can be had to them through the key-hole, without pushing the sliding bolt d upwards, and thus causing a change in the numbers on the indicators, f , g , and h .

The wheels f , g , and h are arranged on the outside of the plate B , and are geared together in the manner indicated in fig. 4, and are confined in a case, C , which is fixed to the plate B , and in which case apertures, 1 2 3, are formed, through which one figure of each wheel f g h can be seen.

On the wheel or indicator *f*, fig. 4, there are the figures 0 and 1 to 9, inclusive, and this wheel is so adjusted that one turn of the key, which is required to open the lock, acting on the slide-bolt and cylinder, as above described, will cause that one of the figures which could be seen through the aperture 1 in the face of the case *C* to disappear, and the figure next in succession to take its place, one complete revolution of the wheel *f* causing ten changes in the said figures. Connected with this wheel, and moved by it by gearing, there is a second wheel or indicator, *g*, fig. 4, numbered in like manner, only that each figure is or may be repeated three, more or less, times, the size of each figure of the same denomination gradually diminishing as it approaches the figure next to it in succession, as shown in fig. 4.

On every complete revolution of the wheel *f*, one of the figures on the wheel *g*, repeated three times, as above described, passes under a point, *s*, in the second aperture 2; ten complete revolutions of the wheel *f* being required to complete one revolution of the wheel *g*, and thus to produce ninety-nine changes in the numbers read off from the two wheels. Connected with the wheel *g*, and moved by it, there is a third wheel or indicator, *h*, fig. 4, numbered in the same manner as the wheel *g*, only that the numbers are placed in reverse order to the numbers on the wheel *g*, as *h* revolves in the opposite direction.

On every complete revolution of the wheel *g*, one of the figures on the wheel *h*, repeated three times, as above described, passes under a point, *s*, in a third aperture, 3, in the face of the lock; ten complete revolutions of the wheel *g*, and one hundred complete revolutions of the wheel *f*, being required to complete one revolution of the wheel *h*, and thus to produce nine hundred and ninety-nine changes in the numbers read off from the three wheels, the numbers on the right-hand wheel, *f*, indicating the unit figures, the numbers on the next wheel, *g*, the tens, and the numbers on the next wheel, *h*, the hundreds. The size of the figures on the last two mentioned wheels diminishes, or may do so, as they approach the numbers next in succession, which must be taken as soon as the stroke between the small and the large numbers appears under the point *s* in the aperture.

When a complete revolution of all the wheels has been made, a projection, *j*, on the third wheel, *h*, is caught by a pin, *i*, which is fastened to the face of the lock by a screw, *k*, figs. 4 and 8, which screw is countersunk, as in fig. 8, the indentation, *l*, being larger at the base than at the top, for the reception of a seal of lead or other material, and which seal, before the screw *k*, by which the pin is fastened, can be taken out, must necessarily be destroyed. Over the three apertures 1, 2, and 3, there is a slide, *m*, fig. 6, by which the said apertures can at once be covered over, so as to protect them from dust and dirt.

The lock is furnished with three, or more or less, bolts, *n*, figs. 2 and 9, each of which not only has an independent action, but catches the shackle *O*, figs. 2 and 5, both at the back and front, thus affording the security of a double number of fastenings, and preventing the lock from being picked by an instrument which does not at once operate in the necessary manner on all bolts.

Having thus described my invention, what I claim as new, and desire to secure by Letters Patent, is—

1. The cylinder *a*, arranged in the lock in such manner that it will cause the motion of the indicator, whenever the key is operated, to open the lock, as set forth.
2. The slide-bolt *d*, by which the cylinder *a* is moved, as described.
3. So constructing the tumblers of a lock that they will lock the cylinder *a*, substantially in the manner herein shown and described.
4. The guard, *p'*, attached to the slide-bolt *d*, for the purpose of protecting the bolts, *n*, to prevent the lock from being picked, as set forth.
5. The application of indicator-wheels, *f g h*, or their equivalents, to a lock, the same being moved or set, whenever the key is turned in the lock, substantially as and for the purpose herein shown and described.
6. The combination of the indicator-wheels with the locking-pin *i*, which can be protected by a seal, as set forth.

The above specification of my invention signed by me, this 15th day of June, 1868.

THOMAS LALOR.
